UNITED STATES PATENT OFFICE.

VANDIVER J. VAN HORN, OF CHICAGO, ILLINOIS.

SUPPORT FOR WASHTUBS AND THE LIKE.

1,012,302.

Specification of Letters Patent. Patented Dec. 19, 1911.

Application filed April 25, 1910. Serial No. 557,434.

To all whom it may concern:

Be it known that I, VANDIVER J. VAN HORN, a citizen of the United States, residing at Chicago, in the county of Cook and State of Illinois, have invented new and useful Improvements in Supports for Washtubs and the Like, of which the following is a full, clear, concise, and exact description, reference being had to the accompanying drawing, forming a part of this specification.

My invention pertains to supports for wash tubs and the like.

The invention particularly relates to supports of that type in which a plurality of legs are provided, the legs being adapted to be secured in convenient positions upon the sides of the tub or the like and having means whereby they may be secured to tubs of varying sizes.

It is the object of my invention to provide an improved supporting member for wash tubs and the like of a simple character and having a clamping device which may be adjusted to fit tubs of any reasonable dimensions. Three or more of the members may be utilized to support a tub.

One of the forms in which my invention may be embodied is illustrated in the accompanying drawings, in which:

Figure 1 shows a wash tub mounted upon my improved supporting members; Fig. 2 is an elevation, partly in section, showing the supporting member as used in connection with a tub having a thick bottom flange; Fig. 3 is a similar view to Fig. 2 but showing the supporting member used in connection with a tub having a thin bottom flange; and Fig. 4 is a perspective view of the clamping member.

My improved supporting member consists of a leg 10, preferably formed of a steel rod or tube having its upper end formed into a hook 11 adapted to engage over the top edge of the tub which is to be supported. The leg is bent adjacent its center so that its upper portion may lie against the wall of the tub while its lower portion will extend outward to provide, with the other legs, a firm support.

Three of the supporting members are shown as being employed to support a tub, but a greater number may be used if desired; or, in case the lower ends of the legs should be forked, a less number might be employed.

Mounted upon each leg is a clamping member 12 which consists of a block having an elongated aperture 13 therein for receiv-

ing the leg. Upon its upper face, at one end, the block is provided with an upwardly extending projection 14 so disposed that it will be spaced some distance from the leg 60 when the clamping member is secured upon the latter. A set screw 15 extends through the other end of the block of the clamping member and is adapted to engage against the leg. By loosening the set screw 15, the 65 clamping member may be adjusted to any desired position upon the leg.

In securing one of the supporting members to a wash tub having a thick bottom flange, as for instance in the case of a wooden 70 tub, the hook 11 is placed over the upper edge of the tub with the leg lying against the side wall. The set screw 15 is then loosened and the clamping member 12 pushed up until it firmly engages against 75 the lower edge of the flange upon the bottom of the tub, with the projection 14 engaging within the flange. The set screw 15 is then tightened, the effect being that the clamping member 12 is secured upon the 80 leg, the projection 14 being drawn, by the action of the set screw, into firm engagement with the inner wall of the flange (Fig. 2). By this means a very firm connection is 85 established. In galvanized iron and other metallic wash tubs the bottom flanges are thin, and, in order to provide for this without unduly elongating the aperture 13, I provide a second clamping projection 16 upon the side of the clamping member opposite to that which carries the projection 14. The projection 16 is so arranged as to be considerably closer to the leg than does the projection 14. When, therefore, the supporting member is to be used in connection 90 with a metallic tub, or one having a thin bottom flange, the clamping member is taken off the leg and replaced with the projection 16 uppermost. The hook 11 is then made to engage over the top edge of the tub and 100 the clamping member secured in place by means of the set screw 15, the projection 16 engaging within the flange of the tub (Fig. 3).

It will be noted that my improved form of 105 supporting leg can be used in connection with tubs varying in depth from the narrowest to the deepest sold upon the market; that the leg may be used in connection with tubs the bottom flanges of which vary in 110 thickness within a wide range; and that the set screws for manipulating the clamping

member are so placed as to be readily accessible. Moreover the supporting members are of so simple a construction that they can be manufactured and placed upon the market 5 at a very small cost.

What I claim as new, and desire to secure by Letters Patent is:

1. A supporting member for wash tubs and the like comprising a leg provided at 10 one end with means for engaging the top edge of a tub, a clamping device sleeved upon said leg and having one side formed with a projection for engaging within the bottom flange of a tub having a thick flange, and 15 having another projection for engaging the bottom flange of a tub having a thin flange, and means for securing the clamping device in position upon the leg.
2. A supporting member for wash tubs

and the like comprising a leg provided at 20 one end with means for engaging the top edge of a tub, a clamping device sleeved upon said leg and having one side formed with a projection for engaging within the bottom flange of a tub having a thick flange, and 25 having another projection for engaging the bottom flange of a tub having a thin flange, and a set screw for securing the clamping device in position upon the leg and arranged so as to draw the projections of said clamp- 30 ing device toward the leg.

In witness whereof, I have hereunto subscribed my name in the presence of two witnesses.

VANDIVER J. VAN HORN.
